UNITED STATES PATENT OFFICE.

WILLIAM BROWN DAVIDSON, ARTHUR CUMMING MICHIE, AND ERNEST WALTER MUDDIMAN, OF NEWCASTLE-ON-TYNE, ENGLAND.

DISTILLATION OF TAR AND THE LIKE.

Application filed April 23, 1926, Serial No. 104,168, and in Great Britain April 1, 1925.

This invention relates to the dehydration and partial distillation of tar or the like, and has for its object to provide improved means for obtaining a distillate which is free from contamination due to frothing or priming of the tar or like substance during the distillation process.

It not infrequently occurs that during the dehydration of certain tars, notably low temperature tars, the contents of the still have a tendency to froth or prime with resulting contamination of the distillate and in some cases serious loss and danger may be incurred due to sudden excessive priming and boiling over of the still contents.

The present invention consists in the elimination of undue frothing of tar or the like, during the process of distillation, by subjecting the froth to contact with a hot surface whereby the froth is immediately broken up and subsides. The invention furthermore consists in the provision of means whereby the dehydration process may progress at a maximum self regulating rate consistent with quiet and continuous operation. The hot surface which may be of any suitable design is maintained at a temperature above that of the originating froth by the circulation of steam or other heating fluid through suitable channels associated with the heating surface.

In carrying the invention into effect a plurality of tubes may conveniently constitute the hot surface and through which the heating fluid is passed at a suitable temperature, said tubes being arranged in the vapour space above the normal level of the substance undergoing distillation. This arrangement is particularly adaptable for use in that type of still in which heat is applied to the contents immediately below the surface, since, according to our invention, we may connect the froth subduing surface with the contents heating means in such a manner that the same heating fluid may be caused to initially traverse the froth subduing surface and then pass through the contents heating means to a final outlet. The froth, which contains a considerable amount of water is broken up upon making contact with the hot surface and causes momentary condensation of some of the heating fluid with the result that less heat is conveyed to the contents heating means

and temporary retardation of the dehydration occurs until the froth subsides.

In order that the invention may be more clearly understood reference is made to the accompanying drawings which illustrate one practical embodiment as applied to a still of the type described in the specification of British Patent No. 196399 and of which Figure 1 is a side elevational view of the apparatus and Figure 2 a sectional elevation of Figure 1 through the line A—A.

Referring now to these drawings the numeral 2 designates in diagrammatic form a series of closely pitched tubes arranged in the vapour space above the level 3 of tar or similar substance in the still. A corresponding series of horizontally extending tubes 4 are located immediately below the tar level 3 and connected by bends or other suitable connections with vertically disposed tubes. Steam is admitted by way of a valve 6 to a steam supply chamber 7 in communication with the inlet ends of the tubes 2, said tubes being arranged in parallel so that steam issuing from the chamber 80 is caused to pass through the individual tubes. By means of the connecting tubes 5 the steam is conducted to the horizontal dehydrating tubes 4 and in so doing imparts sufficient heat to the tar to effect the boiling and distillation.

A similar chamber 8 is provided at the delivery ends of the tubes 4 from which the condensed steam may be led through a pipe 9 to a steam trap or separator. The system of tubes 2, 5, 4 as shown in the illustrated embodiment is of a horizontal U shape formation, thereby obviating troubles due to expansion of the steam tubes upon heating; further precaution may be taken if desired by the provision of supporting rollers extending across the still at right angles to the tubes.

An inlet 10 for crude tar is located at the bottom of the still and is supplied from any suitable pressure means, such as a constant level reservoir, with tar preferably not pre-heated. The dehydrated tar leaves the still through a delivery pipe 11 and may be conducted therefrom for subsequent treatment or storage. A vapour pipe 12 is provided in communication with the vapour space above the upper series of tubes 2 whereby the

vapours formed by the distillation may be discharged from the still.

The hot surface constituted by the closely pitched steam tubes 2 forms an efficient means for breaking up the froth contacting therewith. In the case of the distillation of tar obtained by the low temperature carbonization of coal it is desirable to maintain the steam passing through the tubes 2 at a temperature of about 120° to 160° C. and if no froth is formed the heating tubes 4 will cause adequate boiling of the tar to effect distillation. If however froth is formed, as soon as it is broken up by contact with the hot tubes 2 a certain amount of the steam within the said tubes will be condensed, thus causing less heat to be contained in the tubes 4.

It may be seen therefore that frothing of the tar is accompanied by a corresponding diminution in temperature of the tubes 4, such conditions persisting until the froth subsides whereupon less steam is condensed within the tubes 2 and consequently more heat is conducted to the heating tubes 4. In this manner and by suitably regulating the flow of steam through the valve 7 the system may be caused to operate so that just sufficient heat may be generated in the still as to ensure quiet and continuous operation under varied conditions notwithstanding the formation of froth.

Although we have shown in the embodiment a hot surface constituted by a plurality of steam tubes it should be noted that while the hereinbefore described arrangement forms a convenient manner of adaptation the invention may equally apply to

modified shape and construction of the hot surface.

What we claim and desire to secure by Letters Patent is:—

Apparatus for distilling liquids which froth when heated, comprising a liquid container having an inlet pipe near the bottom, an outlet pipe for maintaining a predetermined liquid level within the container, whereby a vapor space is maintained within the container above the level of the liquid, a plurality of froth disintegrating heating tubes within said vapor space, a plurality of liquid heating tubes positioned slightly below the normal liquid level, each of said heating tubes being directly connected with one of the froth disintegrating tubes, said froth disintegrating tubes having no connections within the container but being connected with a common inlet header exteriorly of the container and said liquid heating tubes having no connections within the container but being connected by a common outlet header exteriorly thereto, whereby a supply of heating fluid may be caused to circulate through said froth disintegrating tubes and also through said immersed heating tubes, the supply of heat being temporarily retarded upon engagement of froth with the froth disintegrating tubes and the heating fluid being discharged from each of said immersed tubes through the common outlet header.

In witness whereof we affix our signatures.
